UNITED STATES PATENT OFFICE.

ALBERT SIMPSON, OF FALUN, ALBERTA, CANADA.

PAPER-DISPENSING DEVICE.

1,384,640.

Specification of Letter's Patent. Patented July 12, 1921.

Application filed October 1, 1920. Serial No. 414,079.

To all whom it may concern:

Be it known that I, ALBERT SIMPSON, a citizen of the United States, residing at Falun, in the Province of Alberta and Dominion of Canada, have invented certain new and useful Improvements in Paper-Dispensing Devices, of which the following is a specification.

This invention relates to improvements 10 in dispensing devices and more particularly to a device of the class described especially adapted for dispensing wrapping paper.

An important object of this invention is to provide a paper dispensing device having 15 novel means whereby the paper may be adjustably tensioned so that it will not move too freely off the roll.

A further object of the invention is to provide a paper dispensing device having 20 novel means whereby the free end of the paper is concealed when the device is not in use so as to prevent meddling with the paper.

A further object of the invention is to provide 25 a paper dispensing device having simple means whereby a portion of the paper may be quickly separated from the roll when desired.

The invention forming the subject matter 30 of this application aims also to provide a device of the class described which is simple to operate, desirable in use and cheap to manufacture.

Other objects and advantages of the invention 35 will be apparent during the course of the following description.

In the accompanying drawings forming a part of this application and in which like numerals are employed to designate like 40 parts throughout the same;

Figure 1 is a perspective of the improved paper dispensing device, parts being shown broken away;

Fig. 2 is a vertical transverse section taken 45 on line 2—2 of Fig. 1;

Fig. 3 is a detail sectional view through the device in operation;

Fig. 4 is a horizontal section taken on line 4—4 of Fig. 1;

Fig. 5 is a perspective of a paper weight embodied in the invention;

Fig. 6 is a detail perspective showing the means for supporting one of the tension strips.

In the drawings, the numeral 10 gener-

ally designates the casing of the improved paper dispensing device and which comprises spaced vertical sides 12 and 13 and upper and lower sides 14 and 15 respectively. As illustrated in Figs. 1 and 2, a 60 roller or shaft 15' extends across the upper portion of the casing and is provided with reduced ends 16 which are rotatably extended through the sides 12 and 13 so as to support a roll of paper 17 within the casing. 65 A paper weight in the form of an elongated body 18 is arranged above the roll of paper 17 and has its end portions arranged within vertical slots 19 extending out through the upper side of the casing, and said paper 70 weight acts to hold the paper tightly about the roll 15'. One end portion of the paper weight is provided with a pair of spaced parallel laterally projecting shoulders 20 arranged to engage opposite faces of the vertical side wall 13 so as to hold the paper weight in position. 75

The rotation of the roller 15' may be limited to one direction by means of a pawl 22 which is pivoted to the side 13 and is adapted 80 to engage a ratchet wheel 24 mounted on the roller. However, when it is desired to reverse the direction of rotation of the roller 15' the pawl 22 may be swung rearwardly on its pivot so as to be supported by a stop 85 element or rest 26.

The paper upon leaving the roller 15' extends downwardly and about a transversely extending guide roller 28 rotatably supported by pivot pins 30 extended through 90 the sides of the casing. The guide roller 28 is arranged rearwardly of a flat transversely extending strip 31 having its end portions seated within notches 32 in the walls 12 and 13. The paper upon passing the guide roller 95 28 is adapted to pass between the stationary strip 31 and a tensioning strip 34 connected to the strip 31 by double hinges 35 so that the strip 34 may be swung upwardly out of contact with the paper. With reference to 100 Fig. 2, it will be observed that the hinges 35 are connected to one longitudinal edge portion of the strip 34 so that when the strip is swung upwardly the same will be caused to entirely clear the paper. The tensioning strip 34 may be locked in contact with the strip 31 by means of a pair of curved locking arms 37 horizontally pivoted at their upper ends to the sides of the casing by means of pivot pins 38. The lower ends of 110

the locking arms 37 are rounded, so that the arms may be adjusted with relation to the tensioning strip 34. That is to say, the arms 37 may be caused to press down hard on the 5 tensioning strip 34 or may be caused to press the tensioning strip down only lightly. The upper side of the stationary strip 31 may be provided with a layer of felt 40.

Upon passing between the strips 31 and 10 34, the paper extends forwardly and passes between upper and lower horizontally pivoted doors 41 and 43 which, as illustrated in Fig. 2, have their opposed edges beveled forwardly and downwardly. The upper longitudinal edge portion of the door 41 carries a hinge 44 which has its end portions extended through the sides of the casing so as to rotatably support the door and permit the same to be swung inwardly or outwardly. 15 Likewise the lower longitudinal edge of the door 43 carries a rod 46 which has its end portions extended through the sides 12 and 13 so as to support the door for swinging movement. Upon passing between the 20 opposed edges of the doors 41 and 43, the paper is adapted to be moved upwardly into contact with the cutting edge of a metallic strip 48 which is secured to the beveled edge of the upper door 41. By thus bringing the 25 paper into contact with the cutting edge of the blade 48, the paper is severed at a point between the doors so that the remaining free end of the same is entirely concealed by the doors. A pair of longitudinally curved leaf 30 springs 50 are secured at their lower ends to the lower side 15 of the casing by means of fastening devices 51 and have their upper ends in contact with the adjacent portions of the doors 41 and 43 so as to normally hold the 35 doors in contact with a pair of rotatably supported retaining elements 53.

As illustrated in Fig. 3, the leaf springs 50 urge the upper door forwardly somewhat in advance of the lower door so that the beveled edges of the same will not conflict when the doors are returned to their normal position. It will be noted with further reference to this figure that the opposed edges of the doors are arranged above the horizontal plane of the upper surface of the strip 31 so that as the doors are moved inwardly to allow the operator to grip the paper, the paper will not be moved inwardly but will remain in position. The retaining elements 55 53 may be rotated and thereby removed from the path of the doors 41 and 43, whereby the springs 50 will be permitted to swing the doors beyond the forward vertical edges of the sides 13 for the purpose of exposing the 60 free end of the paper or for inserting the paper between the strips 31 and 34.

In the use of the device, a roll of paper is arranged in the upper portion of the casing and is passed rearwardly of the guide roller 65 28 and thence between the strips 31 and 34.

Subsequent to passing the paper between the strips 31 and 34, the same is passed between the opposed edges of the upper and lower doors 41 and 43 respectively. When it is desired to sever a portion of the paper or draw 70 the same from the roll preparatory to wrapping a bundle, the adjacent portions of the doors may be moved inwardly with the hand, as illustrated in Fig. 3, so as to expose the free end portion of the paper. The inward 75 movement of the jaws and the gripping of the paper is practically one operation since the thumb is in engagement with the upper door while the index finger may be engaged with the lower door. This places the fingers 80 in position to grip the paper when exposed. Upon drawing the paper from the roll between the doors 41 and 43, the same may by the movement illustrated in Fig. 1 be severed through contact with the blade 48. 85

With reference to the foregoing description taken in connection with the accompanying drawings, it will be apparent that a paper dispensing device constructed in accordance with this invention is capable of readily dispensing the paper in the desired quantity. 90

Having thus described the invention, what is claimed as new is:

1. A paper dispensing device comprising a casing, a paper support arranged within the casing, a fixed tension strip in the casing, a second tension strip above said fixed strip, connections between said strips whereby the second strip will be supported above and normally parallel with the fixed strip and may be moved toward and from the fixed strip, arms pivoted in the casing above the second-mentioned tension strip to bear upon the same and hold it upon paper passing over the fixed tension strip, and means in advance of the tension strips to permit withdrawal of a portion of the paper and sever the withdrawn portion. 95 100 105

2. A paper dispensing device comprising a casing, means whereby a roll of paper may be supported in the casing, a stationary guide strip in the casing, a second guide strip associated with the first named guide strip and adjustable with relation to the same, said actuating strips having flat parallel faces between which the paper passes, and means whereby the paper may be severed, said severing means normally concealing the free end of the paper. 110 115

3. A paper dispensing device comprising a paper support, a pair of horizontally pivoted doors having means for severing the paper, and means whereby the doors may be normally retained in a closed position to conceal the free end of the paper. 120

4. A paper dispensing device comprising means whereby a roll of paper may be supported, guiding means for the paper, a pair of swingingly supported doors having means located at their adjacent portions for sever- 125 130

ing the paper, and spring means urging the doors to a closed position for concealing the free end of the paper.

5. A paper dispensing device comprising
5 a casing, means whereby a roll of paper may
be supported by the casing, upper and lower
doors pivoted to the casing and having their
opposed edges beveled, a cutting blade car-
ried by one of the doors, means to limit the
10 forward swinging movement of the doors,
and spring means urging the doors to a
closed position for concealing the free end
of the paper.

6. A paper dispensing device comprising
15 a casing, means whereby a roll of paper may
be supported by the casing, upper and lower
doors pivoted at their remote edges to the
casing and having their opposed edges bevel-
ed, a cutting blade carried by the beveled
20 edge of one of the doors, means to limit the
forward swinging movement of the doors,
spring means urging the doors to a closed
position for concealing the free end of the
paper, and guiding means for the paper
25 within the casing.

7. A paper dispensing device comprising
a casing, means whereby a roll of paper may

be supported by the casing, upper and lower
doors pivoted at their remote edges to the
casing and having their opposed edges bev-
eled, a cutting blade carried by the beveled
30 edge of one of the doors, means to limit the
forward swinging movement of the doors,
spring means urging the doors to a closed
position for concealing the free end of the
35 paper, guiding means for the paper, and
tensioning devices for the paper between the
guiding means and the doors.

8. A paper dispensing device comprising
a casing, a paper support arranged within
40 the casing, a guiding element carried by the
casing below the paper support, a stationary
strip arranged in advance of the guiding
element, a second strip horizontally pivoted
45 along one longitudinal edge portion to said
casing and arranged adjacent said first
named strip, said strips being in advance of
the guiding element, tensioning means for
said second named strip, and severing means
50 for the paper in advance of said strips, said
paper being adapted to pass between said
first and second named strips.

In testimony whereof I affix my signature.
ALBERT SIMPSON. [L.S.]
